UNITED STATES PATENT OFFICE.

ERNEST DUCHESNE, OF SCHENECTADY, NEW YORK.

LOCOMOTIVE DRIVING BOX.

Application filed July 27, 1922. Serial No. 577,788.

To all whom it may concern:

Be it known that I, ERNEST DUCHESNE, of Schenectady, in the county of Schenectady and State of New York, have invented a 5 certain new and useful Improvement in Locomotive Driving Boxes, of which improvement the following is a specification.

My invention relates to driving boxes for locomotives, and has for one of its objects 10 to provide a driving box in which the journal bearing may be renewed without removing the driving box from the locomotive. Another object is to enable the hub face liner of the driving box to be renewed by 15 dropping the box, without lifting the locomotive. Another object is to provide an improved bearing completely encircling the journal, and to provide additional bearing surface for the driving wheel hub. An- 20 other object is to provide improved means for lubricating the journal; and a still fur- ther object is to simplify the construction whereby the same may be manufactured 25 more economically and without the use of special tools or machinery.

The improvement claimed is hereinafter fully set forth.

In the accompanying drawings: Figure 1 is a vertical longitudinal section through a 30 driving box and hub, embodying my invention; Fig. 2, a side elevation of the same, inside of the frame, and showing one half of the box in section; Fig. 3, a plan; Fig. 4, a transverse section through the upper por- 35 tion of the box, taken on the line 4—4 of Fig. 1; Fig. 5, a view, partly in plan and partly in horizontal section, of the main casting with the other parts removed; Fig. 6, a view, of the same, partly in end eleva- 40 tion, and partly in section; Fig. 7, another view of the same, partly in side elevation and partly in section; Figs. 8, 9 and 10, plan, side, and end views, respectively, of the saddle block, with parts in section; Figs. 45 11, 12 and 13, similar views of the split jour- 50 nal brasses; Figs. 14, 15, 16, 17 and 18, detail views of the parts contained in and for covering the lubricant cellars; Figs. 19, 20 and 21, views similar to Figs. 5, 6 and 7, 55 respectively, but showing a structural modi- 60 fication; and, Figs. 22, 23 and 24, views, similar to Figs. 8, 9 and 10, but showing a 65 modified form of saddle block, adapted to be used with construction of box shown in 70 Figs. 19, 20 and 21.

In driving boxes of the ordinary con-

struction, the main body, or casing, of the box is of an inverted U shaped section, containing a journal bearing, or brass, of semi-circular form, fitting the top half of the 60 axle. When it is desired to renew the bearings, with this construction it is necessary to remove the box from the locomotive, which is a difficult and expensive operation, requiring considerable time and special 65 tools.

In the practice of my invention, referring descriptively to the specific embodiment thereof which is herein exemplified, the main body, or casing, 5, of the box, is of a 70 substantially upright U shape, having a tapered bore for the reception of two split journal brasses, 7, 7. The opening in the upper part of the box is narrower than the outside diameter of the journal brasses, but 75 slightly wider than the diameter of the journal bearing on the axle, so that the box may be placed over the journal when the brasses are not in place.

In the construction shown in Figs. 1 to 80 18 inclusive, of the drawings, a saddle block, 6, is fitted into the open top of the box, and is provided with lugs or projections, 6^a, at both sides, for engaging corresponding recesses or grooves, 5^a, at the upper portion 85 of the box, and thereby preventing any lateral movement of the saddle block. The saddle block is also provided with seats upon which rest the usual spring saddle, 3, which extends over the frame, 1, and the box 90 is formed with flanges for co-operating with the wedge and shoe of the pedestal jaws, 1^a, in the usual manner.

The journal brasses, 7, 7, consist of two symmetrical members, mortised together 95 longitudinally, as shown in Fig. 11, and are tapered on their outside surfaces, to fit the conical bore of the box, 5, and the saddle block, 6. Each segment, 7, is provided with a lateral flange, 7^a, said flanges extending 100 at right angles, and being fitted between pairs of lugs, 5^b, on the face of the box, 5, thus preventing rotation of the brasses within the box. The flanges are secured to the box by stud bolts, 8, by means of which 105 the assembled brasses are drawn into the taper bore of the box, 5, and maintained in firm engagement therewith. A shoulder, 7^c, is formed on the brass, 7, for engaging a corresponding recess in the box, 5, and saddle, 6, thus preventing the brass being drawn 110 too far into the box, and restraining the

saddle from lateral movement. The brasses are bored eccentrically to fit the journal so that their walls are heavier at the top and sides than at the bottom. Orifices, 7^c, are formed in the lower portion of the brasses, 7, 7, adapted to register with cavities, 5^e, communicating with lubricant cellars, 5^d, from which lubricant may be forced to the journal bearing. The cellars, 5^d, may be in 10 the form of twin cylinders, inclined inwardly and containing pistons, 10, and springs, 11, for exerting pressure upon the plastic lubricant usually employed, and causing it to flow toward the journal, the outer ends of 15 the cylinders, 5^d, being closed by a cover, 13, secured by a central bolt, 9. The position of the piston, 10, is shown by the indicating rod, 12, secured to the piston, and extending out through the cover, 13.

20 Another feature of my improvement consists in providing the inside face of the box with a bearing plate or surface, 5^e, and the inner face of the saddle block, 6, has a bearing plate, 6^c, for engaging the wear plate 25 of the wheel hub, so that the hub bearing surface is greatly increased, and presents a continuous wearing face, which completely encircles the journal.

In the modification of the box and saddle block, shown in Figs. 19 to 24 inclusive, the upper part of the box is of a width equal to the outside diameter of the brasses, 7, 7, and is provided with flanges, 5^f, adapted to engage corresponding longitudinal 35 grooves, 6^e, in the saddle block, when the same is slid into place, longitudinally of the axle. The inside vertical faces of the side walls of the box are formed on a taper, as shown in Fig. 19, to fit the taper of the saddle, 6, as shown in Fig. 22, and the saddle block has a pair of lugs, 6^a, to engage the vertical inner face of the flange, 5^f, and maintain the block in position. In other 40 details, this construction is similar to that before described.

It will now be seen that, by the application of my improvement, when it is desired to renew the bearings, the wheels need not be removed from the pedestals, as is required 50 with the ordinary construction, but the weight transmitted through the spring rigging may be removed from the journal by inserting blocks or wedges between the frame, 1, and the spring saddle, 3. The 55 brasses, 7, 7, may then be withdrawn, by making use of the nuts inside of the flange after the outside ones have been removed, and new brasses applied, the box being maintained in position temporarily by inserting blocking above the pedestal tie, 1^b. The renewal of brasses may thus be performed in a simple manner and without the use of special tools.

The feature of the lubricating device, 65 herein shown and described, but not claimed,

forms the subject matter of a divisional application, filed January 30, 1925, Ser. No. 5,760.

I claim as my invention and desire to secure by Letters Patent:

1. In a journal box for locomotives, an upright U-shaped box member having a tapered bore and having recesses in the inner faces of its sides, a saddle having a tapered bore received in the top of said box member and having projections on its sides fitted in said recesses of the box member, exteriorly tapered and mortised journal brasses fitted in the tapered bores of the box member and saddle, each of the brasses having a lateral flange, a pair of lugs on each side of the box member formed to receive the respective flanges of the journal brasses therebetween, horizontally disposed bolts extending through the flanges and into the box member, to draw the brasses into the bores of the box member and saddle, and a shoulder on the brasses to engage the box member and saddle to restrict, inwardly, movement of the brasses and to restrain lateral movement of the saddle.

2. In a journal box for locomotives, an upright U-shaped box member having recesses in the inner faces of its sides, a saddle in the top of said box member having projections on its sides fitted in said recesses of the box member, journal brasses in the box member and saddle, each of the brasses having a lateral flange, a pair of lugs on each side of the box member formed to 95 guidingly receive the respective flanges of the brasses therebetween, and horizontally disposed bolts extending through the flanges and into the box member to enable the brasses to be drawn into the box member.

3. In a journal box for locomotives, an upright U-shaped box member, a saddle in the top of the box member, interengaging means between the sides of the saddle and the respective adjacent sides of the box member, journal brasses in the saddle and box member, a lateral flange on each of the brasses, a pair of lugs on each side of the box member formed to 100 guidingly receive the respective flanges of the brasses therebetween, and horizontally disposed bolts extending through the flanges and into the box member to enable the brasses to be drawn into the box member.

4. In a journal box for locomotives, an 105 upright U-shaped box member, a saddle in the top of the box member, journal brasses in the saddle and box member, a lateral flange on each of the brasses, a pair of lugs on each side of the box member formed to 110 guidingly receive the respective flanges of the brasses therebetween, the lateral flanges being spaced from the front of the box member, horizontally disposed bolts extending through the flanges and into the box mem- 115 ber.

ber, and inner and outer nuts on the bolts, the inner nuts being disposed in the spaces between the box member and respective flanges and engaged with the latter and 5 adapted to urge the brasses outwardly and the outer nuts being engaged with the outer faces of the flanges to enable the brasses to be drawn into the box member.

5. In a journal box, for locomotives, an 10 upright U-shaped box member, a saddle in the top of the box member, journal brasses in the saddle and box member, a lateral

flange on each of the brasses, means carried by the box member to guidingly engage the flanges and hold same and thereby the 15 brasses against rotation, means engaging the outer side of the flanges to move the brasses into the box member, and means engaging the inner side of the flanges to move the brasses outwardly from the box member.

ERNEST DUCHESNE.
